UNITED STATES PATENT OFFICE

HANS R. HEYNE, OF TOLEDO, OHIO, ASSIGNOR TO THE HEYNE-DAVIES ENGINEERING COMPANY, OF TOLEDO, OHIO, A CORPORATION OF OHIO

GAS GENERATOR INSTALLATION

Application filed December 13, 1926. Serial No. 154,438.

This invention relates to gas generators or carburetor installations.

This invention has utility when incorporated in entraining or atomizing means for liquid fuel especially as adapted for domestic lighting, cooking and heating purposes.

Referring to the drawings:

Fig. 1 is a side elevation, with parts broken away, of an embodiment of the invention as 10 a low pressure fuel gas installation;

Fig. 2 is a vertical section through the humidifier and fluid piston device of Fig. 1;

Fig. 3 is a section on the line III—III, Fig. 2, looking in the direction of the arrow;

15 Fig. 4 is a vertical section through the gas generator or vaporizer of Fig. 1;

Fig. 5 is a section on the line V—V, Fig. 4, looking in the direction of the arrow;

20 Fig. 6 is a vertical section through the receiver of Fig. 1;

Fig. 7 is a section on the line VII—VII, Fig. 6, looking in the direction of the arrow; and

25 Fig. 8 is a fragmentary view in plan of the fan or air pump.

Electric motor 1 is shown as having shaft 2 effective through belt 3 for driving pulley 4 on shaft 5 fixed with bladed drum 6 as an air delivery device or fan designed to have 30 a wide range of capacity for delivering against a constant back pressure to be developed and maintained by said fan. From this fan 6 extends pipe 7 upward and then down into vessel 8.

35 This pipe 7 has upturned multiple jet termini 9 disposed below and within chamber 10 fixedly mounted in this vessel 8 by brackets 11, 12, 13. Clamps 14 position the pipe 7 with this chamber 10. Liquid, as 40 water 15, may be in the vessel 8 with free communication through open end 16 as well as port 17 to the interior of the chamber 10. The region of this water 15 within the chamber 10 provides a water piston 18 which, in 45 the normal pump operation, is effective to be depressed to bring the level of the water 15 about the chamber 10 to a desired head for maintained pressure above the port 17.

50 When excessive air pressure is developed within chamber 10 the liquid piston within

said chamber is depressed to uncover port 17 and when this happens the excess air passes through said port and upwardly through the liquid confined between the chambers 8 and 10. As the port 17 is positioned above the jet termini 9 it will be evident that the relief or escape of excess air pressure is effected without depressing the liquid piston sufficiently to uncover the jet termini 9 and hence humidification of the air delivered by the latter at all times is assured. In practice, the motor 6 is so designed that this point of maximum pressure for the water head approximates the back pressure for which the fan 6 is designed. There is ready adjustment below this pressure by the reduction of the head of the water 15 by reducing its quantity. There is accordingly herein an automatic relief valve as a safety device working effectively as a humidifier.

55 This device is a simple relief, insuring safety against excess pressure, while automatically maintaining a reserve as a balance for taking care of widely different rates of fuel consumption without fluctuation of pressure as additional apparatus may be used. From this chamber 10 extends pipe 20 past check valves 21, 22, in duplicate, as one to supplement the other against pressure flow back into the chamber 10 from gas generator container 23. This pipe 20 enters this closed container 23 and extends to the lower portion to have jet termini 24 of discharge capacity area approximating that of the pipe 20 for avoidance of back pressure. The jet termini 9 into the chamber 10 are likewise of an area to take care of the capacity of the pipe 7 at the pressure to be developed normally by the fan 6. These jet termini 24 for the supply of air to the gas generator container 23 are submerged below liquid fuel 25, as gasoline, or other volatile liquid of a suitable character. This container 23 may be charged by the removal of air tight closure cap 26. Cleaning out of this container 23 may occur by the removal of the plug 27 adjacent the bottom. Plug 28 may be removed for washing out the humidifier 8, 10. 60 From the upper portion of this container 23 of the generator extends pipe 29 past check

valves 30, 31, for precluding back flow into the generator 23 of fuel laden air converted into a combustible medium and delivered by this pipe 29 to reservoir 32. As there may be 5 condensation in this reservoir 32 such may be drawn off by the removal of plug 33 near the bottom thereof. In practice, even for plants involving a quite wide range of gas consumption, it may not be necessary or even 10 desirable to include the receiver or reservoir 32, for the humidifier chamber 10 is a pressure equalizing reserve even as against intermittent operation of the fan 6. However, for a supplemental reserve, this reservoir 32 15 is effective and has therefrom gas line 34 to gas consuming equipment as may be desired, as to a hot plate burner 35 having gas flow thereto determined by valve 36. Shutting off this valve 36 checks flow back into the reservoir 32. This does not bring about back flow 20 from this reservoir 32 into the container 23 because the check valves 30, 31, preclude back flow. However, there is built up, in air chamber 37 over fuel 25 in the gas generator container 23, such a degree of back pressure that 25 further flow of supply air thereto by the line 20 is checked. This does not mean a back flow into the humidifier, for the check valves 21, 22, in the line 20, prevent such reverse 30 flow.

If the fan 6 be operating, the delivered air depresses the liquid piston 18 to expose the port 17 and as the fan 6 may continue to operate, such excess of pressure air merely bubbles off out of the vessel 8 and has entrained therewith no combustible mixture or other conditions which tend to develop any fire hazard. At once the valve 36 is opened, pressure flow from the reservoir 32 may be replenished by the generator 23 and humidifier chamber 10 automatically and instantaneously to cut off pressure fluctuation.

With the installation of the reservoir 32 and a capacity for the humidifier chamber 45 10, the motor 1 may be automatically controlled by intermittent operation instead of being run continuously or selectively as the gas equipment is used. To this end the gas delivery line 34 has branch 38 to pressure responsive bellows 39 effective as to upper diaphragm 40 for rocking lever 41 on its pivot bearing 42 in tilting vessel 43 having terminals 44, 45, therein to be submerged by mercury 46 as the pressure in the line 38 falls. 50 This means that electric current supply line 47, as extending to terminal 44, is thus connected to electric line 48 extending to the motor 1 in parallel with electric current supply line 49. There is thus automatically a 55 starting of the motor 1 for operation of the fan 6. As the pressure in the branch line 38 is built up, the bellows 39 operate the lever 41 to again tilt the vessel 43 so that the mercury 46 therein is clear of the terminals 44, 45, and this automatic switch is thus opened.

What is claimed and it is desired to secure by Letters Patent is:

1. Apparatus of the character described comprising a humidifier, a gas generator and a gas storage tank connected together in series, with the humidifier delivering to the gas generator and the latter delivering to the storage tank, a blower functioning to force air through the humidifier to the gas generating tank and to provide the pressure necessary for forcing the generated gas from the generating tank to the storage tank and from the latter to the point of consumption, a motor functioning to drive the blower, a pressure responsive device connected to the gas storage tank and a switch operable by the pressure responsive device to open the motor circuit when the pressure in the storage tank exceeds a predetermined value and to close the motor circuit when the pressure in the storage tank falls below said predetermined value.

2. Apparatus of the character described comprising a humidifier equipped with a storage chamber for humidified air, said chamber having an automatic pressure relief means functioning to prevent the air pressure therein rising above a predetermined value, a gas generator, an air conducting pipe having its inlet connected to the storage chamber of the humidifier and its outlet positioned in the gas generator, a gas storage tank and a gas conducting pipe placing the gas storage tank in communication with the gas generator, a blower functioning to supply air to the humidifier and to provide the pressure necessary for forcing the generated gas from the generating tank to the storage tank and from the latter to the point of consumption, an electric motor functioning to operate said blower, a pressure operated switch connected in circuit with said motor, a gas discharge pipe leading from the storage tank to the point of gas consumption and a branch connection leading from said discharge pipe to the pressure operated switch whereby the switch is opened to break the motor circuit when the pressure in the storage tank exceeds a predetermined value and is closed to reestablish said circuit when the pressure drops to normal.

In witness whereof I affix my signature.
HANS R. HEYNE.
